UNITED STATES PATENT OFFICE.

DEMPSEY LOWE, OF EAST AKRON, OHIO.

MEANS FOR SPLICING INFLATABLE TUBES.

1,179,200.

Specification of Letters Patent. Patented Apr. 11, 1916.

Application filed June 7, 1915. Serial No. 32,712.

To all whom it may concern:

Be it known that I, DEMPSEY LOWE, a citizen of the United States, residing at East Akron, in the county of Summit and State 5 of Ohio, have invented new and useful Improvements in Means for Splicing Inflatable Tubes, of which the following is a specification.

This invention relates to means for splicing inflatable tubes such as are used in pneumatic tires, the object of the invention being 10 to provide simple means for greatly facilitating the formation of perfect overlapping joints between the two extremities of a flexible tube, the means hereinafter described adapting the two end portions of the tube to be manipulated and held in such a manner and in such relation to each other that the cement or other binding agent may be 15 evenly, uniformly and conveniently applied to the surfaces of the tube ends before said surfaces are brought into actual contact with each other.

A further object of the invention is to 20 provide means whereby one end of the tube may be forced by air pressure over the other end of the tube in the process of forming the splice.

With the above and other objects in view, 25 the invention consists in the novel construction, combination and arrangement of parts, as herein described, illustrated and claimed.

In the accompanying drawings:—Figure 1 is a perspective view of the small mandrel 30 or mandrel of least diameter. Fig. 2 is a similar view of the mandrel of larger size constituting the blower mandrel. Fig. 3 is an end view of the larger mandrel. Fig. 4 is a view of the opposite end thereof. Fig. 5 is an end view of the mandrel of less 35 diameter showing the same reinforced along the slot therein. Fig. 6 is a longitudinal section through the end portions of an inflatable tube preparatory to forming the splice therein, showing the mandrels in elevation. Fig. 7 is a similar view showing the relation of the ends of the tube after one end thereof has been forced over the other end thereof by air pressure. Fig. 8 is a detail 40 longitudinal section showing the final condition of the completed splice.

The smaller mandrel or the mandrel of smallest diameter is indicated at 1, the same being generally tubular in construction but 55 provided along the entire length thereof with a slot 2 which is open at both ends of

the mandrel, the slot 2 being designed to admit of the removal of the inflatable tube after the ends thereof have been spliced together as hereinafter described. 60

The larger mandrel indicated at 3 or, in other words, the mandrel of largest diameter, generally resembles the smaller mandrel only in that it is provided throughout the length thereof with a slot 4 open at both 65 ends for the purpose of permitting the tube to be withdrawn from the mandrel after the completion of the splice. The mandrel 3 comprises an outer wall designated by said numeral 3 and an inner wall designated at 70 4, said inner and outer walls being arranged in spaced relation to each other, thereby leaving an intervening substantially annular air space having a substantially annular outlet 5 at the splicing end of the mandrel. 75

6 designates an air inlet which is shown for convenience as located at the opposite end of the mandrel 3 from the outlet 5, air under pressure being forced in the inlet 6 and outwardly through the outlet 5 for a 80 purpose which will presently appear.

The splicing operation is carried out as follows: One end of the flexible and inflatable tube indicated at 7 is inserted through the larger mandrel 3 and then turned backwardly over the air outlet end of said mandrel for a distance equal to the desired amount of overlap in making the splice, the said backwardly turned portion of the tube being indicated at 8. In like manner the 85 other end of the tube is inserted through the smaller mandrel 1 and turned backwardly upon the outside thereof for a considerable distance as indicated at 9 after which the same end portion of the tube is again turned backwardly upon itself to form the inside overlapping end portion of the tube as indicated at 10. The end of the smaller mandrel 1 over which the end of the tube is attached as shown in Fig. 6 is then 90 inserted into the end of the larger mandrel until the parts are brought into the position and relation illustrated in Fig. 6. Adhesive material such as cement combined with an acid for curing the splice is then applied to the exposed surfaces of the end portions 8 and 10 which are to be brought into overlapped and contractual relation to each other. 100

Then air under pressure is forced through the blower mandrel 3 and finding exit through the outlet 5, blows the end portion 8 of the tube off the larger mandrel and over 105

and upon the other end portion 10 of the tube 7.

After the operation above referred to has been completed, the blower mandrel 3 is then 5 slid away from the other mandrel and is removed from the tube by drawing the tube through the slot 4. If desired, binding tape may be passed around the spliced ends of the tube while still in place on the mandrel 10 until the splice has been properly cured. The splice is then drawn lengthwise from the mandrel 1 and the tube is then removed from the mandrel 1 by drawing the same 15 through the slot 2 therein. In this way a perfect splice is obtained between the previously separated ends of the tube.

The wall of the mandrel may be of uniform thickness throughout or the longitudinal edges thereof which define the slot 2 may 20 be internally reinforced as at 11 in Fig. 5 thereby strengthening the tubular mandrel and forming broad abutting faces which bear against each other when the binding tape above referred to is passed around the 25 overlapping end portions of the tube while the cement or other adhesive is curing.

What I claim is:—

1. Means for splicing inflatable tubes, embodying two tubular mandrels one of which is insertible in the other and each of which 30 has a slot extending lengthwise thereof and open at both ends, one of said mandrels comprising an outer wall and an inner wall in spaced relation to each other to leave an air pressure chamber.

2. Means for splicing inflatable tubes, embodying two tubular mandrels one of which is insertible in the other and each of which has a slot extending lengthwise thereof and 35 open at both ends, one of said mandrels comprising an outer wall and an inner wall in spaced relation to each other to leave an air pressure chamber having an air inlet and a substantially annular air outlet at the splicing end of the mandrel.

In testimony whereof I affix my signature in presence of two witnesses.

DEMPSEY LOWE.
